UNITED STATES PATENT OFFICE.

LÉON DION, OF BOSTON, MASSACHUSETTS, ASSIGNOR TO THE ELECTRICAL SAFETY TRACTION COMPANY, OF WEST VIRGINIA.

CLOSED-CONDUIT ELECTRIC RAILWAY.

SPECIFICATION forming part of Letters Patent No. 667,904, dated February 12, 1901.
Application filed August 6, 1900. Serial No. 25,975. (No model.)

To all whom it may concern:

Be it known that I, LÉON DION, of Boston, in the county of Suffolk and State of Massachusetts, have invented certain new and useful Improvements in Closed-Conduit Electric Railways, of which the following is a specification.

This invention relates to electric-railway systems employing a surface conductor composed of a number of insulated sections, a closed conduit, and a flexible conductor contained within said conduit and adapted to be lifted into contact with the surface conductor by the attraction of a magnet carried by the car.

The present invention involves the use of a series of members subject to magnetic attraction and located at intervals along the flexible conductor, whereby said conductor is elevated at intervals into contact with the surface conductor by the passage of a car. One of the objects of such a construction is to permit the closed conduit and the flexible conductor to be located at a considerable distance below the surface of the roadway, its magnetic or armature portions extending upwardly a sufficient distance toward the surface of the roadway to be attracted by the car-magnet when the latter passes.

Of the accompanying drawings, Figure 1 represents a longitudinal section showing a portion of an electric railway constructed in accordance with my invention, together with the car-magnet. Fig. 2 represents a transverse section of the roadway. Figs. 3 to 6, inclusive, represent detail perspective views, hereinafter referred to. Fig. 7 represents a longitudinal section showing a modified form of construction. Fig. 8 represents a perspective view showing a modification in the conduit structure.

The same reference characters indicate the same parts in all the figures.

Referring to the drawings, 1 designates a closed conduit, the top and bottom walls 2 3 of which and preferably also the side walls are made of a suitable insulating construction material, such as wood. The conduit is covered over with an insulating roadway material 4, such as concrete or asphalt. In the form shown in Fig. 1 the material 4 covering

the conduit is traversed at intervals by a number of hollow studs 5 of an inverted-cup shape, as represented in Fig. 4, having their upper ends projecting a slight distance above the surface of the roadway. These studs collectively form a surface conductor composed of insulated sections.

6 is a conductor located within the conduit 1 and composed of a continuous flexible strip 60 of metal which lies loosely within the conduit, so as to be capable of being elevated at intervals by magnetic attraction. The conductor 6 extends through the lower ends of the studs 5 and normally rests upon blocks 7 of insulating material fitted within the studs and having the shape represented in Fig. 3. The conductor 6 is provided within each of the studs 5 with an armature member 8, which, as shown in Fig. 1, consists of a plate riveted 70 to the upper end of a loop 9, formed by bending the conductor 6. The member 8 is made of a suitable magnetic material, such as soft iron, while the conductor 6 may be made of the same metal or a non-magnetic metal, such 75 as copper.

Fig. 6 represents a modification in which the armature member or plate 8 is attached to the upper end of a stem 10, made of any suitable material and secured to the conductor 6. Fig. 5 represents another modification, showing a conductor 6, made of magnetic material, such as soft iron, bent at intervals to form loops 11, the upper ends of which act as the armature members, whereby 85 the conductor is elevated at intervals by the magnet on the car.

12 represents the magnet carried by the car and adapted to attract the armature members of the conductor and lift the conductor 90 at intervals as the car passes along.

13 represents the contact-shoe carried by the car and located in suitable proximity to the magnet 12, said shoe being adapted to make contact with a plurality of the studs 5 95 at the same time. As the magnet 12 passes over each of the studs 5 it attracts the armature member 8 within said stud and lifts the conductor 6 into contact with the lower end of the stud, the contact taking place between 100 the points 14 15 on the stud and conductor. The insulating-block 7 is so shaped as to pre-

vent contact at other points or when the conductor is depressed in its normal position. It will be observed that this construction permits the main body of the conductor 6 to be located at any desired distance below the surface of the roadway, while its armature members project upwardly within attracting distance of the car-magnet.

In the modification shown in Fig. 7 the upper ends of the studs 5 are extended and joined together by plates 16 16, which form a nearly-continuous contact-surface and insure a smooth runway for the contact-shoe 13.

I do not herein claim a surface conductor located below the surface of the roadway and having a series of contact-studs projecting above the roadway-surface, nor do I claim a magnet carried by the car and inclosed in a casing at the lower end of which is a collecting-shoe, as represented in Fig. 1, these constructions being claimed, respectively, in two pending applications, serially numbered 707,859 and 707,857, filed by me March 6, 1899.

It is obvious that, although not herein illustrated, a suitable feeder or feeders may be employed, after the ordinary manner, in connection with the conductor 6.

I prefer to make the surface conductor of any suitable metal or alloy which is not subject to magnetic attraction—such, for example, as manganese-steel.

I do not limit myself to the details of construction here shown and may variously modify the same without departing from the spirit of the invention.

Fig. 8 represents a modified form of conduit structure in which three walls of the closed conduit are formed by the sides of a groove 19, cut in a wooden beam 17; the top wall being formed by the surface conductor, which is made up of insulated plates 18, having the hollow studs 5 formed on them and projecting upwardly therefrom.

I claim—

45 1. In an electric railway a closed conduit having a surface conductor comprising inverted-cup-shaped sections insulated from each other.

50 2. In an electric railway a closed conduit having a surface conductor comprising inverted-cup-shaped sections insulated from each other and composed of metal not subject to magnetic attraction.

3. In an electric railway, a closed conduit, 55 a surface conductor composed of insulated sections, and a movable conductor contained within the conduit and consisting of a flexible strip of metal subject to magnetic attraction,

bent at intervals to form raised portions which act as armatures to the car-magnet, whereby 60 the movable conductor is elevated at intervals into contact with the surface conductor by the passage of the car.

4. In an electric railway, a closed conduit having a series of pockets in its upper wall, 65 with conductive upper ends constituting a surface conductor, a conductor contained within the conduit and having raised movable armature members in said pockets, and provisions for effecting connection between the 70 surface conductor and the conduit-conductor by the elevation of said armature members due to the attraction of the car-magnet.

5. In an electric railway, a closed conduit located below the surface of the roadway and 75 covered over with insulating material, a surface conductor consisting of insulated sections and having hollow conductive portions which extend through the said conduit-covering insulating material to the interior of 80 the conduit, and a flexible conductor contained within the conduit and having a series of members arranged at intervals above the main body of the conductor, within said hollow portions, and composed of metal subject 85 to magnetic attraction, said members acting as armatures to the car-magnet, whereby the flexible conductor is elevated at intervals into contact with the lower ends of the hollow portions of the surface conductor.

90 6. In an electric railway, a closed conduit, a surface conductor composed of insulated sections, and a flexible conductor contained within the conduit and having a series of raised members projecting above the conduit 95 and adapted to conduct electricity from the flexible conductor to the car-motor.

7. In an electric railway, a closed conduit, a surface conductor composed of insulated sections, and a flexible conductor contained 100 within the conduit and having a series of raised members projecting above the conduit and adapted to conduct electricity from the flexible conductor to the car-motor, the said closed conduit having a series of pockets 105 which receive the raised members of the flexible conductor and have conductive upper ends constituting sectional surface conductors.

110 In testimony whereof I have affixed my signature in presence of two witnesses.

LÉON DION.
